(76) Inventor: **William Wiard**

William Heward
Letters Patent Issued January 26th, 1821

The Schedule referred to in these Letters Patent, & making part of the same, containing a description in the words of the said William Heward himself of his improvement in the Plough.

My improvement consists in the mode of putting in the edge in the plan of locking in the main lands side to the mould board in the mode of attaching an additional side to the lower portion of the lands side, in placing a whole thimble in the main lands side immediately behind the handle & directly opposite this whole thimble, in the mould board, into which a rivet is received, & lastly in the manner in which the structure is constructed & situated.

My Plough is constructed of four different pieces viz. The mould board, lands side, colgd. & the piece which is locked on the lower portion of the lands side to be hereafter described.

First. The mould board differs from the one in common use in the following particular. The edge is put on entirely different from the manner in which it has hitherto been done in the common plough; this piece is screwed on, which renders it unnecessary to put it on & take it off as occasion requires, the edge is placed on my plough by means of a loop which is passed thru' a corresponding mortice in the mould board, this loop after having passed thru' the mould board is wood overkey, is driven which secures it on its place & renders it extremely easy to be put on & removed, moreover, in the colgd. are two dowels or knobs that are received into two small round conical excavations in the mould board, which they exactly fit in. The short lands side differs from the common one in the manner in which the main lands side is attached to it - in its receiving in its lower extremity an additional

piece to be retouched described is in its being connected in a pointed manner with the Standard board which continues up from this short, ^{land} ~~land~~ nearly to the same breadth with it until it ^{comes} ~~comes~~ meets the ^{land} ~~land~~ beam, & at the mouth of the board ^{land} ~~land~~ ^{beam} must be bent the handle symmetri-
cally above the lower loop into which the extremity of the han-
dle is received, this half handle is for the reception of one
extremity of the above mentioned board & when this is
cannot be connected until the handle which is attached
to the mouth board is taken off, will disengage the jaws
of the thumbler which is held in part different. — These
are the principal points of difference in my strength
from all others at ^{the} mouth the mouth board. Secondly
the main handle there are three points in which this
differs from all others, namely, 1st the manner the handle is
which it is connected to the short land side of the mouth
board, which is done in the following manner, — The extremity
is received into an ^{exterior} ~~exterior~~ ^{exterior} point by the projection of the
inner part of the main land side. & the angle formed
by the connection of the mouth board with the short land side.
In addition to this resting place formed by the projection
of the inner part of the short land side, it has three other
namely two, and are received into its extremity from the
short land side into the main land side which will ^{allow}
it to pass over one other directly or ^{allow} ~~allow~~ of the short land
side about two inches & a half above the last mentioned,
in addition to these three connections the main land side
has a projecting extremity or ^{allow} ~~allow~~ received into the short
land side about ^{allow} ~~allow~~ inches above the last mentioned connection
or resting place on the main land side. — From the mouth
board about three inches from the extremity of the main land
side there projects as in all ploughs a small knot
which helps to preserve the extremity of the piece now

described in its place. Before the outside of this main band
ride, &c., at the lower part of it is placed an additional piece
of nearly the same length, so as to cover the outside of the
movable band. This piece is connected to the main band ride
by two loops which pass ~~thru~~¹ it, when two wooden pegs are
driven thru' them to receive the compass. This piece is about
two inches & a half or three inches broad & about half
an inch in thickness. This piece receives nearly all if not
quite all of the wear which takes place in the use of
the strength, in the band ride. Just behind the hummer
is the "hump" above mentioned. Directly opposite to the
half division also above-mentioned between which is found
one, & this is placed which keeps the hummer loose. The
main band ride at the proper distance apart, —
the short band ride with in between these two cast steel
bands, placed a bout of four inches. Instead of the loops
mention'd in the specification above for the hummer
of the strength, any other iron staples may be used.

In testimony that the above is a true description or
specification of my above mentioned improvement, I
have hereunto set my hand this 27th day of Decem.
